(57) **CLAIM**

The ornamental design for a support frame assembly, as shown.

DESCRIPTION

FIG. 1 is a top and side isometric view of a novel support frame assembly embodying the present invention;

FIG. 2 is a reverse isometric view thereof;

FIG. 3 is a reverse rear isometric view thereof;

FIG. 4 is a rear isometric view thereof;

FIG. 5 is a left side elevational view thereof;

FIG. 6 is a right side elevational view thereof;

FIG. 7 is a top plan view thereof;

FIG. 8 is a bottom view thereof; and

FIG. 9 is a top and side dimetric view thereof.

FIG. 10 is a top side isometric view of a further novel support frame assembly embodying the present invention which illustrates the large leg component of the assembly shown in FIG. 1 and further showing a disconnected smaller support component thereof;

FIG. 11 is a reverse isometric view of FIG. 10;

FIG. 12 is a reverse rear isometric view thereof of FIG. 10;

FIG. 13 is a rear isometric view of FIG. 10;

FIG. 14 is a left side elevational view of FIG. 10;

FIG. 15 is a right side elevational view of FIG. 10;

FIG. 16 is a top plan view of FIG. 10;

FIG. 17 is a bottom view of FIG. 10;

FIG. 18 is a top and side dimetric view of FIG. 10;

FIG. 19 is a rear elevational view of FIG. 10, but further showing the support component coupled to the leg component;

FIG. 20 is a front elevational view of FIG. 10, but further showing the support component coupled to the leg component.

FIG. 21 is a top and left side isometric view of another novel support frame assembly embodying the present invention comparable to that shown in FIGS. 1-9, but wherein the rear and side faces thereof are perpendicular to one another and the outwardly facing bottom flange at the lower end thereof shown in FIG. 4 thereof is directed inwardly and not outwardly;

FIG. 22 is a bottom, rear and side isometric view of FIG. 21;

FIG. 23 is a rear and side isometric view of FIG. 21;

FIG. 24 is a bottom and left side isometric view of FIG. 21;

FIG. 25 is a right side elevational view of FIG. 21;

FIG. 26 is a left side elevational view of FIG. 21;

FIG. 27 is a top plan view of FIG. 21;

(Continued)

FIG. 28 is a bottom view of FIG. 21;
FIG. 29 is a rear elevational view of FIG. 21; and,
FIG. 30 is a front elevational view of FIG. 21.
